UNITED STATES PATENT OFFICE.

RICHARD W. HANNA, OF PIEDMONT, CALIFORNIA, ASSIGNOR, BY MESNE ASSIGNMENTS, TO STANDARD OIL COMPANY OF CALIFORNIA, OF SAN FRANCISCO, CALIFORNIA, A CORPORATION OF DELAWARE.

ART OF DISTILLING LUBRICATING OILS.

Application filed October 4, 1923. Serial No. 666,475.

This invention relates to improvements in the art of distilling petroleum oils and has to do particularly with the distillation under vacuum of lubricating oils.

In the preparation of lubricating oils, difficulty is frequently encountered by the formation of emulsions during the treatment of the lubricating oil distillates with acid and alkali. These difficulties include ineffectual neutralization of the organic acidity in the lubricating oils, a material loss in yield suffered through the removal or drawing off of the emulsified oil, a material drop in color during brightening operations, and a lack of color stability in the finished oil. These troubles are especially pronounced when the stock used to produce the lubricating oils is from an asphaltic or mixed-base crude.

Various causes have been ascribed for these emulsions; chief of these are: The production of certain reaction compounds during the acid treatment, and the presence in the oil of solids in finely-divided state in suspension, or solids in colloidal form or state as distinguished from solids present in true solution. While it is undoubtedly true that both of these causes are present, it has been determined that a partial cause of the more permanent emulsions encountered in the production of lubricating oils is due to the presence of certain tarry, heavy and asphaltic bodies, particles and constituents carried over with the vapors from the distilling equipment in the form of a "mist" or spray. The carrying over of these tarry particles or "mist" with the vapor is especially prevalent when the distillation is carried on under a reduced pressure.

When these tarry bodies are carried over into the lubricating oil distillates, not only are additional emulsion troubles encountered, but the acid treating yield is materially lowered, required color is more difficult to obtain, and greater skill on the part of the treating operators is required in order to produce an oil meeting the required standards. Furthermore, the resulting lubricating oils invariably give a poor precipitation test.

In the distillation operation for the production of lubricating oil distillates, very material advantages are obtained when the entire composite or crude lubricating oil stock, comprising the light as well as the

heavy lubricating oil constituents, is fed into a single distilling unit operated continuously and at a uniform or constant temperature for the vaporization therefrom of all the different lubricating oil constituents. When the distillation is thus conducted, so that the vapors from the higher-boiling-point oils are evolved simultaneously and in a commingled state with the vapors of the lower-boiling-point oils the temperature at which the higher-boiling-point oils can be vaporized is materially reduced. When such distillation is conducted continuously and at greatly reduced pressure and preferably with the use of steam, the temperature at which the highest-boiling-point oils may be vaporized is so reduced that decomposition of such oils by "cracking" is substantially prevented and a material increase in the production of the desired high-boiling-point and high-viscosity lubricating oil distillates made possible.

When these advantages in the distilling operation are used to obtain an increased production of the high-boiling-point and high-viscosity lubricating oils, it will be apparent that, in the evolving of all the vapors of the various fractions in a commingled state, there will be an increased tendency to carry over with the evolved vapors a "mist" comprising the undesirable tarry particles before referred to.

It will also be apparent that when the advantages of the single continuous distillation operation under vacuum are employed and the vapors of the high-boiling-point oils and the lower-boiling-point oils are evolved simultaneously and in a commingled state, a subsequent separation of the evolved products into the various desired grades of lubricating oil fractions becomes necessary.

In order to thus employ the distillation advantages incident to evolving simultaneously and in a commingled state, all the vapors of the various lubricating oil distillates and at the same operation to obtain clean, well-fractionated and separate grades of lubricating oil fractions or distillates, free from the tarry constituents or "mist" which are carried over in the vapors during the distilling operation, I extract from the commingled evolved vapors this "mist" before fractionation or condensation of the vapors.

Furthermore, through use of such "mist"

extraction and fractional condensation, as employed in my invention, I am able to eliminate from the resulting lubricating oil distillates, substantially all of the light oils, 5 such as gas oil, residual lamp oil and other light constituents which have remained in the crude lubricating oil stock from former topping operations and which, if permitted to remain in the lubricating oil fractions, 10 would lower the flash-point of the oils to such an extent that when the desired viscosity is reached in a given lubricating oil fraction the flash-point would be too low to meet the required specifications and a re-running or 15 reducing distillation operation will be necessary to eliminate such light and undesirable oils and bring the flash-point up to requirements.

My invention thus makes possible the operation of a single continuous distilling unit 20 under a reduced pressure less than atmospheric, and the simultaneous production of a number of different grades of lubricating oil distillates without the necessity for condensing the evolved vapors in a commingled state and subsequently separating the various stocks by fractional distillation, and also without the necessity of reducing the separate fractions for the required flash- 25 point. In addition to having the required flash-point corresponding to the viscosity of the respective distillates, these oils are free from the tarry constituents or "mist" which promote emulsion troubles during subsequent 30 chemical treatment. Due particularly to the extraction of the tarry constituents, particles or "mist" from the commingled vapors before condensation, an increased treating yield and a better precipitation test are obtained on the resulting oils than could be 35 otherwise obtained.

The invention in its several aspects may be better understood and comprehended in connection with a description of a process 40 comprising a preferred embodiment of the invention, and by reference to the accompanying drawings which illustrate apparatus in which may be performed such a process. The indicated apparatus is given for illustrative purposes only, and it is to be understood that the arrangement shown and the details of construction illustrated may be widely varied without departing from the scope of my invention. Furthermore, the 45 invention in its several separate aspects is of the scope set forth in the appended claims and not necessarily limited in each of its respective aspects to all of the steps detailed in the description of a process comprising a 50 preferred embodiment of the invention.

In the drawings: In Fig. 1 I have indicated an apparatus by means of which a process embodying my invention may be performed. In the apparatus as described in this figure, I have illustrated means for pre-

heating the oil to be heated so as to materially increase the rate of evolution of the commingled vapors, giving an increased yield for the same charging rate or for the same yield, permitting an increased charging rate. In Fig. 2 I have illustrated an apparatus of simpler form omitting the step of high pre-heating of the oil to be treated before its introduction into the vaporizing still. Fig. 3 illustrates a form of fractionating condenser which may be employed. Fig. 4 illustrates a re-heating fractional condenser which may be employed as a part of the apparatus. Fig. 5 is a sectional plan view of the means employed for extracting the tarry particles or "mist" from the vapor; and Fig. 6 is a longitudinal vertical section thereof.

Referring to Fig. 1:

2 represents a storage tank or source of supply. 3 represents the feed-line of the system in which is a suitable pump 4 for supplying the oil to be distilled through the feed-line 3 under suitable pressure and by which the desired velocity of flow is maintained. The feed-line 3 passes through a vapor heat exchanger 5, of ordinary or any preferred construction, and thence passes through a residuum heat exchanger 6, of ordinary or any preferred construction, and thence through the heating coil 7. This heating coil is mounted in a suitable furnace 8 and heated by suitable means, such as, for example, a burner 9. From this heating coil 7 the heated oil passes to a still or vaporizing chamber 10. In line between the coil and the outlet into the vaporizing chamber 10, I interpose a suitable pressure controlling valve 12, which may be set to maintain such pressure as may be desired or required. The form, shape or design of the still or evaporating chamber 10 may be varied as desired, and its form or shape or construction forms no part of the present invention. As shown, this still or evaporator 10 is mounted over a suitable furnace 13 provided with heating means, such as a burner 14. In practice, the evaporator may be heat-insulated to prevent radiation losses. 15 represents the vapor outlet line which passes from the evaporator 10 to the "mist" extractor 85. This "mist" extractor is preferably in drum form and the interior chamber thereof is provided with a suitable number of series of vertically arranged channels 86. These channels are preferably formed by suitable metallic plates. The series of channels are arranged in staggered relation so that the intermingled vapors flowing into the chamber of the "mist" extractor must flow around and between the channel-irons of the respective series before passing out of the "mist" extractor from the opposite side. The contact of the vapors with the metallic surfaces of the channel-irons causes a pre-

cipitation of the tarry constituents, particles or "mist" which are withdrawn from the "mist" extractor through the outlet 87 and conducted by the pipe or conduit 88 back 5 into the evaporating chamber or still 10, preferably at or near the bottom thereof. From the outlet side of the "mist" extractor chamber the vapor line 15 extends through the vapor heat exchanger 5 and thence to the 10 inlet chamber 30 of the re-heating fractional condenser 31. From this inlet chamber 30 the vapors pass through the tubes 32 into the outlet chamber 33 and thence by the pipe 34 to a second fractional condenser 35. 15 This fractional condenser 35 may be of the form and construction illustrated in Fig. 3. After circulating through the chamber of the condenser 35, the uncondensed vapors pass through the outlet pipe 36 and into a 20 second fractional condenser 37. This fractional condenser 37 may be of the ordinary or any preferred construction, such, for instance, as the fractional condenser of Fig. 3. 38 represents the vapor outlet pipe from the 25 fractional condenser 37. This outlet pipe leads into the condensing chamber 39 of the re-heating fractional condenser 31, above the upper pipe or tube 32. Within this chamber 39 are mounted a series of pans 40 pref- 30 erably circular in cross-section and suitably mounted in the condenser 31, as by suitable brackets or straps (not shown) welded to the inner shell of the condenser 31. Between adjoining pans 40 are interposed horizontal partitions 41 welded to the inner surface of the shell 31. These shells are provided at their centers with flanged openings as shown, of less size or diameter than the size or diameter of the pans 40. The rising 35 vapors from the inlet pipe 38 are thus caused to pass through a curtain of descending condensate dropping from the lower partition 41 to the lower pan 40 and through successive curtains of descending condensate in 40 passing around successive pans and up through the openings in successive partitions 41 and into the vapor-line 42. This vapor-line 42 is connected with a final fractional condenser 43, from which condenser the 45 lightest distillate produced is withdrawn. 44 indicates the pipe or line by which the said distillate is withdrawn from the condenser 43. This pipe or conduit 44 is connected to a suitable storage tank (not shown) passing first through a suitable cooling coil 45 (see Fig. 2) in a suitable cooler 46 and thence through look-boxes 47 and a receiving drum 48. This receiving drum is connected by a suitable line with a distillate 50 storage tank E, a suitable suction-pump 49 being interposed in this line. The receiving drum 48 is connected by a suitable line 21 with the vacuum pump 20. 22 (Fig. 2) represents the exhaust from the vacuum 55 pump. As this latter and apparatus and connections as shown in Fig. 2 may be readily connected to and used in the apparatus indicated in Fig. 1, I have not deemed it necessary to extend and show the same in Fig. 1. 50, 51, 52 indicate respectively the 70 conduits or lines leading from the lower portions of the condensing chambers of the condensers 37, 35, 31, respectively. These respective conduit lines 50, 51, 52 are connected (as indicated in Fig. 2) through suitable cooling coils 45 in coolers 46 and thence through suitable look-boxes 47 to receiving drums 48 and thence to distillate storage tanks or drums C, B, D, respectively. Each of the receiving drums is connected with the vacuum pump 20. 53 represents a condensate line leading from the chamber 33 of the condenser 31 and is in turn connected through a suitable cooling coil 45 in a cooler 46, through a suitable look-box 47 and to a suitable receiving drum 17 and thence through a distillate pump and line to a distillate storage tank A. 54 represents a cooling medium supplying conduit connected with a suitable source of supply (not shown). This cooling medium is preferably water. As indicated in both Fig. 1 and Fig. 2, the direct line of this conduit 54 is through the valve 55, coil 56 in the chamber 39 of the re-heating fractional condenser 31, and thence back to discharge. A branch line 57 leads through a valve 58 into the condenser 43, passing downward through the tubes or pipes 59 thereof and out through the conduit 60 into the return leg of the line 54. 61 represents a valve in this line. The inlet portion of the line 54 is connected just beyond the branch 57 with a branch line 62 which communicates into the discharge conduit 60 below the condenser 43. 63 represents a suitable valve in this line. From the feed-line 3 leads a branch pipe 64, by means of which the relatively cool oil to be treated may be used as a cooling medium for the condensers 35, 37. By using such feed-oil as a cooling medium in such condensing operation, heat economy is effected and the feed-oil after passing through the condenser 37 and thence the condenser 35, is returned to the line 3, at raised temperature, by the return leg 65 of such conduit. 66 and 67 represents suitable valves controlling this conduit. The branch conduit 64 is connected directly with the condenser 37, and the feed-oil, after passing downward through the tubes thereof, passes into the return leg 65 through the pipe 68. A branch 69 leads from the line 64 to the condenser 35, and the condenser 35 is connected at its bottom by a pipe 70 with the return leg 65. 71 represents a branch pipe or conduit connected with the line 64 between the branch 69 thereof and the condenser 37. This branch line 71 is connected with the outlet line 68 of the condenser 37. 130

4

72, 73, 74, 75, 76 and 77 indicate suitable valves by which the flow of cooling medium through this cooling system may be controlled and regulated as desired. 78 indicates a valve interposed in the line 3 between the branch 64 and the return leg 65 thereof so that by suitable regulation of the valves 66, 67, 78, the circulation of feed-oil for this cooling system may be controlled and directed. 27 represents a steam-line leading into the still or evaporating chamber 10, the end 28 of such steam-line being preferably in the form of a perforated pipe located near the bottom of the evaporating chamber. 29 indicates a valve controlling such steam-line. The steam-line 27 is connected to a suitable source of steam supply (not shown). 23 represents a residuum draw-off line which passes through the residuum heat exchanger 6 and through a cooler 25 to the residuum storage 26. If desired, the oil to be treated may be discharged into a suitable evaporating pan 11 in the upper portion of the still or evaporating chamber 10. 84 indicates a steam-line or source of supply by which, if desired, steam may be introduced into the condensing chamber 39 of the re-heating condenser 31. This steam-line 84 is connected with any suitable source of steam supply (not shown).

Referring to Fig. 2: The apparatus as illustrated in this figure of the drawings is in all essentials similar to that illustrated in Fig. 1, except that the apparatus and connections for high fire pre-heating of the feed-oil are omitted. I have, therefore, in these two figures of the drawings used the same reference numerals as indicating corresponding parts. In Fig. 2 the oil-cooling and pre-heating branch line 64 is shown as provided with a branch line 79 connecting to the feed-line 3 beyond the residuum heat exchanger 6, and the return leg 65 is shown as provided with a branch line 80 connected with the feed-line 3 beyond the residuum heat exchanger 6. A valve 81 is interposed in the feed-line 3 between the connections of the lines 79 and 80 therewith, and the lines 79 and 80 are respectively provided with valves 82, 83. The oil to be treated, after passing through the feed-line 3 and residuum heat exchanger 6, may by means of regulation of the valves 81, 82, 83, be passed into the cooling branch line 64 and back into the line 3 by the return leg 80, thus utilizing the partially heated oil when so desired.

In the preferred embodiment of my invention in a process of distilling the composite basic stock containing all the different lubricating oil fractions to produce lubricating distillates ready for treating and finishing as lubricating oils, the first step is the pre-heating of such stock to be treated to a much higher degree than can economically be obtained by the use of heat exchangers by which the waste heat of the system is utilized, i. e.: at temperatures below 400° F. I have found that a material increase in the rate of evolution of the commingled vapors from this composite stock is obtained, giving an increased yield for the same charging rate or for the same yield, permitting an increased charging rate, when the stock fed into the distilling chamber is pre-heated to temperatures higher than can economically be obtained by the use of such waste heat exchangers, i. e.: when such stock is heated to above 400° F. This pre-heating of such stock may be extended up to 800° F., and is conducted at pressures higher than those under which distillation takes place, after which the heated oil may be injected into a vaporizing chamber held at pressures less than atmospheric. This pre-heating may or may not be carried on in the presence of steam or water vapor, the vaporizing chamber may or may not be supplied with additional heat after the highly pre-heated oil is injected therein, and the vaporization may or may not be carried on in the presence of steam. I, therefore, pass the body of oil to be distilled through the heating element 7 in relatively small streams and maintain as high a velocity of the oil passing therethrough as is consistent with the heat transfer from such heating element to the oil and the mechanical conditions and adaptations of the particular apparatus and discharge the heated oil into the vaporizing chamber as quickly as possible after it has been raised to such temperature. I maintain such a pressure of the evolved vapors in the heating coil and conduit to the vaporizing chamber as may be required under the conditions of operation to substantially maintain the oil as it is being heated, and when heated, substantially all in liquid phase. Vaporization of such heated oil is effected in a single vaporizing chamber under a reduced pressure less than atmospheric. Under certain conditions of operation I have distilled oil in accordance with my process with as high as 26 inches of vacuum in the vaporizing chamber.

In a modification of my preferred process, the oil, instead of being heated in the heating element to the highest degree of temperature utilized in the distilling operation, may be heated only approximately thereto and a reasonable rise in temperature of the body of the oil effected in the vaporizing chamber by the application of exterior heat, as by means of a burner 14, and either with or without the use of steam therein. However, in such a modification and embodiment of my invention, the body of oil heated in the heating element is raised to such a temperature that it may be brought to the highest temperature of the distilling operation without the necessity of such a heat transfer in

the evaporating chamber as will cause material "cracking" of any portions of the oil therein. Where in the heating element 7 the temperature of the oil to be distilled is raised above the "cracking" temperature of portions thereof, the oil being maintained substantially all in liquid phase therein by maintaining suitable pressure thereon, the oil is quickly discharged, after reaching the desired temperature, into the vacuum vaporizing chamber 10 so that the heated oil is not subjected to such "cracking" temperature for a sufficient time to permit of the "cracking" reaction. In such case, if the insulation of the vaporizing chamber 10 is sufficient, it may not be necessary to supply any exterior heat whatever to the vaporizing chamber to vaporize the desired fractions. Heat may be supplied to such vaporizing chamber 10 by means of external heat, as, for example, the furnace 13 and burner 14, to impart to the oil loss of heat by radiation or evaporation or to impart additional heat so long as the heat demand upon the shell of the evaporating chamber is not sufficient to cause substantial "cracking" of portions of the oil undergoing distillation. With such fired pre-heating of the oil, where using certain California oils, I have found by raising such oil in the heating element to the temperature of 750°-800° F., and retaining the same in liquid phase, immediately injecting such heated oil into a vaporizing chamber under vacuum, vaporization of the desired fractions of the oil takes place without "cracking". If, however, it is desired to vaporize a higher-boiling-point or more viscous fraction or fractions, some additional heating may be required in the vaporizing chamber. Without such additional heat supply in the vaporizing chamber, the resultant liquid oil may be maintained therein at substantially 630° F. Temperatures even above 630° F. have been thus attained in the liquid body in such vaporizing chamber. If only the heat lost by radiation is supplied to the vaporizing chamber, this temperature of the oil in the vaporizing chamber is held uniform, i.e., there is no differential temperature between the body of such oil and the shell of the vaporizing chamber. Furthermore, by applying additional heat to the vaporizing chamber in any degree less than sufficient to cause "cracking" or decomposition at the contact between the shell of the vaporizing chamber and the oil therein, a still higher temperature may be maintained in such oil body. By thus delivering the oil to be distilled into the vaporizing chamber at such increased temperature, I am able to attain a marked increase in the charging rate and, therefore, an increased capacity for the production of high-boiling-point and high-viscosity oils. Also I am able to cut deeper and produce more high-boiling-point and high-viscosity oil

from a given stock. In certain runs the rate of charging must be properly proportioned to permit the vaporization of such higher-boiling-point and higher-viscosity oil. The lubricating oil thus produced is of a marked superior quality. Aside from having a high boiling point and a higher viscosity, due to higher temperatures and deeper cuts employed, I produce a higher-viscosity oil due to the absence of "cracking" compounds. A better color is also maintained and the treating loss will be found to be reduced.

If, however, it be not desired to utilize this feature of high fired pre-heat and maintaining the oil in liquid phase by pressure during such pre-heat and the immediate discharge of the highly pre-heated oil into the vacuum chamber before "cracking" takes place, I have found that the oil can be subjected to a progressively increasing heat, materially higher than that obtained by the use of waste heat exchangers, but to a lower temperature than that obtainable in the heating element 7 as heretofore set forth. For example, utilization of the waste heat of the operation cannot economically be utilized to raise the oil to be distilled to above 400° F. Additional heat may be supplied to the oil by means of the heating element 7 to raise the temperature thereof to any desired degree below the "cracking" temperature of any appreciable portion thereof, and if such temperature is not sufficient for the vaporization of the desired high-boiling-point, high-viscosity fractions desired to be distilled, the required additional heat can then be supplied in the vaporizing chamber without danger of "cracking", inasmuch as the temperature of the oil has been raised to such an approximation of the temperature of the desired distilling operation that the heat differential between the body of oil to be distilled as injected into such vaporizing chamber and the shell temperature required for the required heat transfer from the vaporizer 10 to the oil is not sufficient to cause such an abrupt and excessive raise in the temperature of the oil particles in contact with the heated metallic surface as will cause "cracking" thereof. I am, therefore, in this modified embodiment of this pre-heating step of my invention, able to conduct such distilling operation at a higher temperature without "cracking" than has heretofore been possible. Increased capacity, increased charging rate, or deeper cut, is thus rendered possible.

It is obvious that this highly pre-heated oil may be injected into the vacuum vaporizing chamber either above or into the liquid therein. If desired, such oil may be injected onto a spreading-pan, as indicated at 11 in the drawings, or other spreading or distributing means.

From the foregoing it is seen that this

step of high fired pre-heating of the stock to be distilled comprehends in its several aspects the continuous distillation at a pressure below atmospheric, by first heating such 5 oil to be distilled at a pressure higher than that under which distillation takes place, such heating being effected either with or without the presence of water vapors or steam and to a temperature higher than 10 can be economically obtained by the use of heat exchangers utilizing the waste heat of the system, i. e.: to temperatures between 400° F. and 800° F., injecting such heated oil into a chamber maintained at a pressure 15 less than atmospheric, which chamber may or may not be supplied with additional heat, depending upon the degree to which the oil has been heated before interjection therein, and in which chamber additional steam may 20 or may not be injected, as preferred, the manner of injecting the highly heated oil into the vacuum vaporizing chamber being preferably above the surface of the liquid therein in such a manner as to expose the 25 maximum vaporization surface to facilitate distillation, although if desired such injection may be below the surface of the liquid therein. Also the step comprehends a continuous feed, a continuous vaporization and 30 continuous withdrawal of the evolved vapors, and the withdrawal of the residual unvaporized product either continuously or intermittently, as desired.

Preferably, all of the vapors to be distilled 35 from the stock are vaporized and pass off the oil together. The mixture of relatively higher and relatively lower-boiling-point oils all vaporized simultaneously will be found to have the effect of vaporizing relatively 40 higher-boiling-point fractions than would be vaporized at the given temperatures were such higher-boiling-point fractions vaporized alone after the vaporization of such relatively lower-boiling-point fractions. All 45 of such vapors are withdrawn from the vaporizing chamber intermingled and pass to the condensing apparatus. It is obvious that after these vapors have been so produced, the tarry particles, constituents or 50 "mist" may be separated therefrom by a "mist" extraction as by the "mist" extractor 85 at any preferred time before passing to condensation. For example, while I have shown such "mist" extractor 85 as arranged in the vapor-line 15, the "mist" extractor may be arranged within the vaporizing chamber or still 10 or as a dome thereof or in any other suitable relation to the withdrawal of the vapors from the chamber 10, and prior to condensation of such vapors.

The next step of my invention is to separate and segregate the intermingled relatively lower-boiling-point and relatively higher-boiling-point oils contained in the intermingled vapors withdrawn from the

vaporizing chamber. It is highly advantageous to effect this separation in such manner and under such conditions that the produced condensates will be distillates of the desired boiling points and viscosities and not require re-running or reducing to provide a stock ready for treating and finishing as lubricating oil; also to remove from the respective distillates those lighter and lower-boiling-point constituents which serve to contaminate the distillates produced by lowering the flash-point thereof.

In the preferred embodiment of a process embodying my invention, therefore, I prefer to utilize the high heat of the intermingled vapors as withdrawn from the vaporizing chamber as a means for re-heating the condensate of the relatively lower-boiling-point oils. I, therefore, pass these intermingled vapors through closed conduits contained within a chamber, to which chamber is returned the vapors of the lighter or lower-boiling-point fractions, said returned vapor being brought to a lower temperature by a controllable cooling means located within said chamber whereby a reflux results from said returned vapor, and re-heating this reflux through the means of the heat of the total intermingled evolved vapors passing from the evaporating chamber or still through said passages of said chamber, thereby revaporizing and separating from such reflux those light fractions which are low in flash-point. This step of the process may be more readily understood in connection with the detailed explanation of such preferred embodiment. I will, therefore, trace the course of passage of the withdrawn intermingled vapors of the distilling operation through the steps of condensation and segregation. The highly heated vapors first pass into the chamber 30 of the re-heating fractional condenser 31 and pass through the tubes 3 thereof into the chamber 33. The descending condensate from the upper chamber 3 contacts with the tubes 32 highly heated by the passage of the vapors therethrough, and this condensate or reflux is thus re-heated and those light fractions which are low in flash-point are revaporized and the resulting condensate from which they are separated is withdrawn through the pipe or conduit 52 to the distillate storage tank D. The effect of this heat transfer is to cause certain condensation of the highest-boiling point vapors in the chamber 33. This condensate is drawn off from the chamber 3 by the pipe 53 to the storage tank A. The vapors passing from the chamber 33 through the conduit 34 and into the condenser 3 are further cooled therein and the condensate forming therein is withdrawn through the pipe 51 to the distillate storage tank I. The vapors passing from the condenser 3 through the pipe 36 to the condenser 37 at

further condensed in the latter and the condensate therein formed drawn by the pipe 50 into the distillate storage tank C. The vapors ascending from this condenser 37 5 pass by the vapor conduit 38 into the chamber 39 of the re-heating fractional condenser 31, wherein they are partially condensed, the condensate subjected to re-heating as before described, and the vapors pass out through 10 the vapor-line 42 and into the final condenser 43, the condensate of which is drawn by the pipe 44 into the storage tank E. From the foregoing description, it will readily be seen that by this controllable fractional condensation of the intermingled 15 vapors of distillation I am able to produce distillates of the desired boiling point range substantially free from low-flash-point oil, and that each of these distillates is completely 20 distilled and forms an oil ready for treatment and finishing as a lubricating oil. Re-running or reducing is obviated.

While in the preferred process forming a preferred embodiment of my invention I 25 prefer to utilize the relatively cold fresh feed of the oil to be distilled as the cooling medium for the condensers, (such as condensers 35, 37,) of the intermediate distillates, and to use water circulation as the 30 cooling medium for controlled regulation of the condensation in the initial or final condensers, it is obvious that any controllable cooling medium may be used for these purposes, and the invention is not necessarily 35 limited to the use of either water or of the fresh feed stock as the cooling medium.

I claim:

1. In the art of petroleum distillation, heating the oil to be distilled to the temperature at which portions thereof would crack if maintained at such temperature for a period of time sufficient to permit the cracking reaction to take place while maintaining the same in substantially a liquid phase, passing 45 the heated oil before substantial cracking thereof takes place to a vaporizing chamber maintained under a reduced pressure less than atmospheric wherein the temperature of the oil is permitted to drop below the 50 temperature at which portions thereof would crack, withdrawing vapors from said

chamber, extracting from the vapors the tarry "mist" without substantial scrubbing of vapors in said step, and thereafter fractionally condensing the vapors into a number of distillates of different boiling points. 55

2. In the art of petroleum distillation, heating the oil to be distilled to a temperature at which portions thereof would crack if maintained at such temperature for a period of time sufficient to permit the cracking reaction to take place, while maintaining the same in substantially liquid phase, immediately passing the heated oil before substantial cracking thereof takes place to a 60 vaporizing chamber, maintained under a reduced pressure less than atmospheric, wherein the temperature of the oil is dropped below the temperature at which portions would crack, extracting from the vapors the 65 tarry "mist" without substantial scrubbing of vapors in said step, and thereafter fractionally condensing the vapors into a number of distillates of different boiling points. 70

3. In the art of petroleum distillation, rapidly passing the oil in a relatively small stream through a heating element, thereby raising the temperature thereof to the temperature at which portions of said oil would crack if maintained at such temperature for 75 a period of time sufficient to permit the cracking reaction to take place, while maintaining such oil in substantially liquid phase by suitable pressure, immediately discharging the heated oil before substantial cracking thereof occurs, into a vaporizing chamber maintained under a reduced pressure less than atmospheric, wherein portions of the oil vaporize, thereby causing the temperature of the oil to drop below the temperature at which portions thereof would crack, 80 withdrawing the resultant vapors, suitably withdrawing the resultant unvaporized product, extracting from the vapors the tarry "mist" without substantial scrubbing 85 of vapors in said step, and thereafter fractionally condensing the vapors into a number of distillates of different boiling points. 90

Signed at Richmond, California, this 25th day of Sept., 1923.
